UNITED STATES PATENT OFFICE.

HENRY RUPPEL, OF CLEVELAND, OHIO, ASSIGNOR TO AMERICAN STOVE COMPANY, OF ST. LOUIS, MISSOURI, A CORPORATION OF NEW JERSEY.

PERFORATED COMBUSTION-TUBE.

1,159,102.

Specification of Letters Patent.

Patented Nov. 2, 1915.

Application filed May 12, 1915. Serial No. 27,651.

To all whom it may concern:

Be it known that I, HENRY RUPPEL, a citizen of the United States, residing at Cleveland, in the county of Cuyahoga and State of Ohio, have invented certain new and useful Improvements in Perforated Combustion-Tubes, of which the following is a specification, reference being had therein to the accompanying drawing.

10 My invention relates to improvements in perforated combustion tubes.

The object of my invention is to provide a perforated combustion tube which will cause the gas and air to properly mix as they travel up, so that when the gas reaches the upper end of the tube the proper mixing of the air has taken place so that an absolutely odorless flame is obtained.

Another object of my invention is to provide a simple, cheap and more effective perforated combustion tube having certain details of structure and arrangement of parts hereinafter more fully described.

In the accompanying drawings, Figure 1 is a vertical sectional view of the perforated combustion tube embodying my invention and showing it applied to the ordinary wick burner. Fig. 2 is a transverse sectional view taken on the line 2—2 of Fig. 1. Fig. 3 is a vertical sectional view broken away of a modified form of combustion tubes.

In perforated combustion sections of the ordinary type in which two straight concentrically arranged tubes have been used and between which the gas is mixed with the air, it has been found that the air and gas do not at all times properly mix so as to insure the proper mixture and the burner often throws off a disagreeable odor owing to the fact that the air and gas have not been properly mixed. Owing to the arrangement of the corrugations of my improved tubes, or the corrugations of the jacket, the air and gas are thrown against the corrugated walls of the tubes and obviates the difficulties found in perforated combustion tubes having two concentric tubes.

Referring now to the drawings, 1 represents the inner combustion tube and 2 the outer combustion tube which have at their lower ends the vertically disposed concentrically arranged portions 3 and 4 which rest upon the inwardly and outwardly extending flanges 6 and 5 carried by the upper ends of the concentrically arranged wick

tubes 8 and 7. The construction of the wick tube is of the ordinary form now used and needs no further description. The perforated combustion tubes 1 and 2 above the vertically disposed portions 3 and 4 are corrugated throughout their entire length whereby the zigzag passage 9 is formed and whereby the passage of the air and gas upwardly through the said passage causes them to be thrown against the corrugated walls of both the inner and outer tubes 1 and 2 thus causing a perfect mixing of the air and gas so that when they reach the upper end of the combustion tubes the proper mixing of the air and gas has taken place and thus gives an absolutely odorless flame.

The inner combustion tube 1 is provided adjacent its lower end with the diaphragm 10 and adjacent its upper end with a diaphragm 11 having openings therein, all of which is well understood and needs no further description. The inner combustion tube 1 extends about one-half inch above the outer combustion tube 2 so as to permit the free escape of the flame when the burner is covered with a cooking vessel. The upper end of the inner perforated combustion tube 1 has a solid top 12. This extended end of the inner combustion tube also prevents a certain amount of the flame deflecting back between the tubes when the burner is covered and it also makes a much better looking flame. While I have shown and described this specific arrangement and combination of parts to accomplish the desired results, it will be understood that the same could be varied without departing from my invention.

In the modification shown in Fig. 3 the inner combustion tube 13 has its walls straight while the outer tube 14 is corrugated. By this arrangement it has been found that the air and gas will be thoroughly mixed. While I have shown the inner tube straight and the outer tube corrugated, it will be understood that the inner tube can be corrugated and the outer tube straight with the same results.

Having thus fully described my invention what I claim and desire to secure by Letters Patent is:

1. A combustion section comprising concentric tubes having corrugations oppositely arranged and extending in the same direction for the purpose described.

2. A combustion section comprising two

- concentric combustion tubes having corrugations extending around the same and the opposite corrugations extending in the same direction for the purpose described.
5. A combustion section comprising two concentrically arranged tubes having corrugations extending therearound throughout their entire length and oppositely arranged and extending in the same direction to form 10 a zigzag passage between the perforated tubes.
4. A combustion section comprising two concentric tubes each having a plurality of oppositely arranged corrugations extending 15 in the same direction to form a zigzag passage between the tubes for the purpose described.
5. A combustion section comprising two concentric tubes having oppositely arranged 20 corrugations extending in the same direction to form a zigzag passage between the tubes, the inner tube extending slightly above the outer tube.
6. A combustion section comprising two concentric tubes having straight lower ends 25 and in a horizontal alinement and having oppositely arranged corrugations extending in the same direction to form a zigzag passage between the tubes and the inner tube extending a slight distance above the outer 30 tube, substantially as shown and described.
7. A combustion section comprising two concentric tubes having separate lower ends in a horizontal alinement and having oppositely arranged corrugations throughout 35 their entire length and extending in the same direction to form a zigzag passage between the tubes, and the inner tube extending a slight distance above the outer tube and having a closed upper end, substantially as shown and described.

In testimony whereof I hereunto affix my signature in the presence of two witnesses.

HENRY RUPPEL.
